1

This application is a continuation-in-part of my application Ser. No. 516,265, filed December 30, 1943, now abandoned, entitled High frequency coil with variable inductance.

The present invention relates to induction coils with adjustable inductance, more particularly to a variable induction coil structure for use in connection with a condenser to provide a tuning or resonant circuit of variable resonant frequency.

According to known methods of varying the inductance of a coil, the effective inductance of the coil is controlled by means of a sliding contact moving either spirally along the individual coil turns or in the direction of the coil axis. A disadvantage of arrangements of this type is the fact that the contact with the wire is highly inefficient and subject to considerable wear during use, and that furthermore the free or open end of the coil constitutes an undesirable oscillating system causing interference and other defects well known.

It has also been proposed heretofore to vary the inductance by means of a non-magnetic metal ring or cylinder arranged to displace the magnetic flux of an induction coil, said ring or cylinder being adjustable in an axial direction and being arranged either outside or inside said coil. In inductance coils of this latter type considerable eddy current losses are produced, while the adjusting range of the inductance is relatively limited.

According to the present invention, the above disadvantages are substantially avoided by the provision of an adjustable non-magnetic metal of this type member associated and cooperating with the coil windings in a novel manner, whereby the alternating current through the coil is passed at least in part through said metal member by way of the inherent electrical capacity between said member and the adjacent coil winding turns.

The invention, both as to its further objects and novel aspects, will become more apparent from the following detailed description of a few practical embodiments and applications, taken in reference to the accompanying drawings forming part of this specification and wherein:

Fig. 1 shows schematically the basic construction of a variable induction coil embodying the principles of the invention;

Fig. 2 shows an equivalent electrical circuit diagram explanatory of the operation and function of Fig. 1;

Fig. 3 illustrates a modification of Fig. 1;

2

Fig. 4 shows an equivalent circuit diagram for the construction according to Fig. 3;

Fig. 5 and Fig. 6 are circuit diagrams illustrating, by way of example, the employment of an induction coil according to the invention in a push-and-pull vacuum tube circuit;

Fig. 7 shows an improved adjustable induction coil according to the invention designed to increase the accuracy of the inductance control;

Fig. 8 shows still another modification of a variable induction coil structure embodying the principles of the invention, and

Figs. 9, 10 and 11 are circuit diagrams illustrating further practical applications of the invention.

Like reference characters identify like parts throughout the different views of the drawings.

Referring more particularly to Fig. 1, the induction coil shown at 10 may be of any suitable construction, that is either of the self-supporting type or wound upon a suitable support in a manner well known. A non-magnetic hollow metallic cylinder 11 concentrically surrounding coil 10 is arranged to be displaced or shifted in an axial direction. For this purpose, the cylinder 11 is shown provided with a pair of spaced annular flanges 12 and 13 which are in turn provided with openings at their upper ends through which is passed a fixed guide rod 14. Additional threaded openings at the lower ends of said flanges cooperate with a threaded spindle carrying an adjusting knob 16 at its extreme end. Thus, by turning knob 16, the cylinder 11 may be displaced axially with respect to the coil 10, whereby to cause the ratio of the free or open coil portion A—B to the covered or enclosed coil portion B—C to vary in a manner well understood. Any other device or mechanism for adjusting the cylinder 11 may be employed for the purpose of the invention.

If the distance of the winding turns of coil 10 from the inner surface of the cylinder 11 is small compared with the distance between adjacent winding turns, the mutual inductance between the individual winding turns inside the cylinder will be practically negligible. The enclosed portion of the coil between points B and C covered by the cylinder 11 may therefore be replaced by an equivalent straight conductor having a length equal to the stretched or unwound length of the enclosed coil portion B—C and being spaced from a conducting surface by a distance equal to the spacing of coil 10 from the cylinder 11. In other words, coil portion B—C

enclosed by the cylinder 11 represents a two-wire Lecher line whose length depends upon the portion of the cylinder 11 covering or enclosing the coil 10. The length of the free or uncovered portion between points A and B is simultaneously varied in the opposite sense by the adjustment of cylinder 11, as is understood.

In the embodiment of the invention shown in Fig. 1, the inner end C of coil 10 is connected to the outer end of cylinder 11 at point D through a flexible conductor as shown, a sliding contact arrangement, or in any other suitable manner. Cylinder 11 is in turn connected at its inner point E, to the electrical circuit in which the coil is to be inserted, i. e. terminal b, the remaining terminal a of the coil being connected to the beginning of the coil winding at point A. In the example shown, points A and E are furthermore connected to a fixed condenser 17, the connection to point E being through a flexible conductor or the like, to provide an adjustable parallel-resonant or tuning circuit, whose terminals a and b may be connected in any desired system or circuit such as an amplifier, oscillator or the like. Alternatively, the coil terminals A and E may be connected to the condenser 17 in series to obtain a series-resonant circuit in accordance with well known practice.

In Fig. 2 there is shown an equivalent electrical circuit diagram of the coil structure described hereinbefore. The inductance of the open or effective coil portion identified by numeral 10' is in series with the Lecher line 10''-11' formed by the adjustable cylinder corresponding to conductor 11 and the adjacent ineffective coil winding turns corresponding to conductor 10'', the remaining reference characters having the same significance as those of Fig. 1. In this modification of the invention, the end C of coil 10 inside the cylinder 11 is directly connected to the latter as indicated by the direct or conductive connection between points C and D. The Lecher line 10''-11' thus acts mainly as a simple capacity which, compared with the inductance of the effective coil portion 10', may be neglected for all practical purposes.

In place of a metallic contact between the coil 10 and the cylinder 11, it is possible to provide a capacitative connection such as in the form of a cylindrical condenser, by connecting the end C of the coil to a fixed solid cylinder 18 arranged inside the hollow sliding cylinder 11, as more clearly shown in Fig. 3. In the latter, the axial adjustment of the cylinder 11 has been indicated merely schematically by the double arrow x. The adjustment may be effected by a mechanism similar to that shown in Fig. 1 or by any other suitable means as will suggest itself to those skilled in the art.

Fig. 4 shows the equivalent circuit diagram of the construction shown in Fig. 3 which differs from Fig. 2 merely by the capacity 19 bridging the ends C and D of the Lecher line 10''-11'.

In many cases the conductive or capacitative connection between the coil 10 and sliding cylinder 11 may be omitted, whereby the equivalent diagram of the enclosed coil portion represents an open Lecher line which, if of short length, constitutes a pure capacity for all practical purposes. This capacity between the equivalent Lecher wire conductors 10''-11', Fig. 4 may also be used as a circuit element passing the electric current of the circuit in which the coil is connected, as shown in the embodiments of the invention described in the following.

There is thus provided by the invention a non-resonant induction coil of adjustable inductance devoid of variable contacts or the like and which may serve as an effective tuning reactance in a resonant circuit comprising said coil and a condenser connected therewith either in parallel or series. In order to prevent undesirable losses due to radiation, the coil is designed as small as possible in relation to the wave length of the high frequency current passing through it in operation. In other words, the natural resonant frequency of the coil due to its distributed capacity should be substantially higher than the resonant frequency of the resonant circuit of which the coil forms an effective tuning element.

According to one embodiment of the invention, the adjustable induction coil described may be advantageously used in connection with a push-and-pull vacuum tube circuit, as shown in Fig. 5. In the latter, the anodes of the two push-and-pull connected amplifier tubes 20 and 21 are connected in a known manner to a tuned circuit comprising the condenser 17 shunted by two variable induction coils 22 and 23 which are constructed in accordance with the invention and connected in series with each other. The series connection of coils 22 and 23 is effected, in the example illustrated, through the Lecher line capacities between the ineffective or covered portions of the coils and their associated sliding cylinders 24 and 25, respectively, said cylinders being both electrically and mechanically connected through a member 26 for uni-control or synchronized adjustment, as indicated by the arrows x. If several circuits or amplifying stages are to be tuned simultaneously, it is advantageous to control all of the circuits in synchronism by directly mechanically connecting all the tuning cylinders, inasmuch as all stages, if designed equally will have the same frequency variation characteristic. Small deviations from the synchronized operation may be corrected by the provision of additional or trimmer condensers or by any other suitable means known in the art.

According to the arrangement shown in Fig. 6, two coils according to the invention are employed for effecting an exact electrical symmetry in a symmetrical push-and-pull circuit, by displacing a common sliding cylinder 28 relative to the symmetry point of the circuit and in the direction of the common axis of the coils 20 and 21, as indicated by the arrow x.

In order to effect a clear separation between the ineffective or enclosed and the effective or free coil portion, to improve the accuracy of the inductance control, the sliding cylinder may be constructed in the manner shown more clearly in Fig. 7. In the latter, the cylinder 11 is arranged to perform a screw-like or spiral movement, with the pitch of the spiral movement substantially corresponding to the pitch of the coil winding turns. Accordingly, the coil windings will always be exactly underneath the helical shaped projecting nose 30 of the cylinder 11 which is cut off perpendicularly to the coil winding turns.

According to a further modification of the invention, the sliding cylinder may be arranged on the inside instead of on the outside of the coil as shown in the preceding illustrations. Such an arrangement is shown in Fig. 8. In the latter, the sliding cylinder 11 which in this case may be either a hollow or a solid cylinder is arranged for axial movement inside the coil 10. There is shown for this purpose a cup-shaped guiding

member 31 or hollow cylinder and a piston-like member 32 sliding therein and adjustable by means of a threaded spindle 33 suitable journaled in the end wall of member 31 and carrying an adjusting or operating knob 34. The piston 32 is normally urged into engagement with the inner end of spindle 33 by a spring 35 in such a manner as to afford a continuous axial adjustment of the cylinder 11 by rotation of the knob 34. Any other mechanism or device for axially adjusting the cylinder 11 within the coil 10 may be employed for the purpose of the invention.

According to another modification of the invention, the capacity between the coil and the sliding cylinder may be increased by using an adjustable member consisting of two cylinders, one arranged inside and the other being arranged outside the coil. If the cylinder is given a screw-like or spiral motion, the effective capacity may be further increased if the cylinder surface nearest the coil is shaped so as to conform with the profile of the coil winding turns. The capacity between the sliding cylinder and the coil may also be increased by using a coil made with square or flat wire of rectangular or square cross-section.

In many cases it has been found advantageous to employ a conical or tapering sliding cylinder in connection with a cylindrical coil, or alternately to employ a conically wound coil together with a straight cylinder in order to provide a variable distance between successive winding turns of the coil and said cylinder. In this manner, the capacity between the coil and the sliding cylinder will be a function of the adjusting position of the cylinder, such as in the case of Figs. 5 and 6, and may be varied or controlled to suit any special requirements.

Referring to Fig. 9, there is shown another practical application of a variable tuning coil according to the invention. The circuit shown represents a two-stage push-pull amplifier comprising amplifier tubes 37 and 38 and 40, 41 and fixed tuning condensers 42, 43 and 44, 45, respectively. The two sliding cylinders 11 for each stage are connected with each other both electrically and mechanically and arranged for simultaneous adjustment by means of a common operating member indicated schematically at 46. The anode voltage for the tubes of each stage is advantageously applied through the tuning coils, suitable decoupling or by-pass condensers to ground being provided as shown at 46 and 47, respectively. The input and output terminals of the circuit are shown at c—d and e—f, respectively.

Referring to Fig. 10, there is shown a single resonant anode circuit connected to an amplifier tube 48 and comprising a fixed tuning condenser 50 shunted by an adjustable induction coil of the type according to the invention as shown in Fig. 3. Condenser 51 of large capacity represents the usual by-pass or decoupling capacity for the anode voltage supplied through the coil 10 from a suitable source. In this arrangement, the sliding cylinder 11 is substantially free and not in any way directly or conductively connected in the circuit. The high frequency current is transmitted through the relatively large capacity between the sliding cylinder 11 and the fixed cylinder 18, the latter being connected to the end of coil 10 in substantially the same manner as shown and described with reference to Figs. 3 and 4.

Referring to Fig. 11, there are shown a pair of series resonant or trap circuits including adjust-

able induction coils according to the invention. The inductance of the upper coil 10 of the type according to Fig. 3 together with condenser 52 represents the first series-resonant circuit and similarly the induction of the lower coil 10 together with condenser 53 represents the second series-resonant circuit. Both series-resonant circuits are connected, in the example shown, in a symmetrical two-wire line having input terminals c—d and output terminals e—f, the latter being connected to the fixed cylinders 18 on the one hand and to a load such as a symmetrical cable 56, on the other hand. The two series-resonant circuits may serve to suppress undesirable harmonics in the currents being transmitted, while freely passing the current of fundamental frequency to which the circuits are tuned. This circuit arrangement also dispenses with any direct circuit connection of the sliding cylinders 11, in that the high frequency currents are again directly transmitted through the capacity between the cylinders 11 and 18, respectively.

While there have been shown and described a few desirable embodiments of the invention, it is understood that this disclosure is for the purpose of illustration and that various changes in shape, proportion, and arrangement of parts, as well as the substitution of equivalent elements for those herein shown and described may be made without departing from the spirit and scope of the invention as defined in the appended claims. The specification and drawings are accordingly to be regarded in an illustrative rather than in a restrictive sense.

I claim:

1. A variable high frequency inductance comprising a pair of induction coils, a pair of cylindrical non-magnetic metallic members each arranged in spaced and electrically isolated relation to one of said coils, means for electrically connecting said members, whereby to connect the inner ends of said coils adjacent to said members through the mutual capacities between said coils and members, and means for simultaneously axially displacing said members, the outer ends of said coils serving as terminals of said inductance.
2. A variable high frequency inductance comprising a pair of induction coils, a pair of cylindrical non-magnetic metallic members each arranged concentric to and in spaced and electrically isolated relation to one of said coils, the spacing distance between said coils and members being small compared with the distance between adjacent coil winding turns, means for electrically connecting said cylinders, whereby to connect the inner ends of said coils adjacent to said members through the mutual capacities existing between said coils and said members, and means for simultaneously axially displacing said members, the outer ends of said coils serving as terminals of said inductance.
3. A variable high frequency inductance comprising a pair of substantially identical induction coils, a pair of identical non-magnetic metal cylinders each arranged concentric and in spaced and electrically isolated in relation to one of said coils, means for electrically connecting said cylinders, whereby to connect the inner ends of said coils adjacent to said cylinders through the mutual capacities between said coils and cylinders, and means for simultaneously axially displacing said cylinders, the outer ends of said coils serving as terminals of said inductance.
4. A variable high frequency inductance com-

prising a pair of induction coils, a pair of non-magnetic hollow metal cylinders each arranged concentric to and overlying one of said coils in spaced and electrically isolated relation thereto, the spacing distance between said coils and said cylinders being small compared with the distance between adjacent coil turns, means for electrically connecting said cylinders, whereby to connect the inner ends of said coils enclosed by said cylinders through the mutual capacities between the said coils and cylinders, and means for simultaneously axially displacing said cylinders, the outer ends of said coils serving as terminals of said inductance.

5. A variable high frequency inductance comprising a pair of substantially identical induction coils, a pair of identical non-magnetic hollow metal cylinders each arranged concentric to and overlying one of said coils in spaced and electrically isolated relation thereto, the spacing distance between said cylinders and said coils being small compared with the distance between adjacent coil winding turns, means for electrically connecting said cylinders, whereby to connect the inner ends of said coils enclosed by said cylinders through the mutual capacities between said coils and cylinders, and means for simultaneously axially displacing said cylinders, the outer free ends of said coils serving as terminals of said inductance.

6. A variable high frequency inductance com-

prising a pair of substantially identical induction coils, a pair of identical non-magnetic hollow metal cylinders arranged each coaxially with and overlying equal portions one of said coils in spaced and electrically isolated relation thereto, means for directly continuously and mechanically connecting said cylinders whereby to connect the inner ends of said coils enclosed by said cylinders through the mutual capacities between said coils and cylinders, and means for simultaneously axially displacing said cylinders, the outer ends of said coils serving as terminals of said inductance.
